IRA H. SPENCER, OF WEST HARTFORD, CONNECTICUT, ASSIGNOR TO THE ORGAN POWER COMPANY, OF HARTFORD, CONNECTICUT, A CORPORATION OF CONNECTICUT.

AIR-PUMP.

1,184,040.

Specification of Letters Patent. Patented May 23, 1916.

Application filed August 27, 1915. Serial No. 47,712.

To all whom it may concern:

Be it known that I, IRA H. SPENCER, a citizen of the United States, and a resident of West Hartford, in the county of Hartford and State of Connecticut, have invented a new and Improved Air-Pump, of which the following is a specification.

My invention relates more especially to that class of devices employed for creating flow of a current of air, and an object of my invention, among others, is to provide a device of this class that shall be especially applicable for use in connection with musical instruments, as organs, by reason of its quietness in operation.

One form of device embodying my invention, and in the construction and use of which the objects herein set out, as well as others, may be attained, is illustrated in the accompanying drawings, in which—

Figure 1 is a view in central lengthwise section through a pump embodying my invention. Fig. 2 is a detail view in cross section through the driving shaft showing parts supported thereon and one of the fans in face view.

In the operation of fans or pumps to place air in proper condition for use in musical instruments, it frequently happens that the vibration incident to the operation of such apparatus causes a sound, often similar to a deep bass note, which is transmitted through the tubes for conveying the air or otherwise so that it is audible within the zone within which the notes of the instruments are heard, and it is to avoid this and other objectionable sounds, and to otherwise improve the construction that I have produced the device described herein and shown in the accompanying drawings, in which the numeral 5 denotes a case preferably formed of metal, circular in cross section, and having a compartment closed at its ends by plates 6—7. An exhaust opening 8 provides for the outflow of air from the case through an exhaust pipe 9 to which a conduit is attached, and through which the air flows in connection with the musical instrument with which it is used, said air being supplied to a reservoir or otherwise as the circumstances may require. A shaft 10 is connected with or comprises an extension of the shaft of the motor 11, the end of the shaft opposite the motor, in the construction herein shown, being unsupported.

All of the parts herein above described are of old and well known construction and except in connection with other parts of the device to be hereinafter described form no part of the present invention.

I have found that if the fans are loosely connected with the driving shaft that much of the objectionable noise will be prevented, and in carrying out this idea I mount the hub of each fan loosely upon the shaft 10, that is, so that said hub, except for its driving connection, may be rotated independently of the shaft, suitable devices being employed for holding the hub in its proper position lengthwise of the shaft. The hubs may be differently arranged with respect to the rest of the fan and to suit varying conditions, two examples being shown herein in which the hub 12 of one fan is located on that side of the flange 14 that supports the fan blades 15 while the hub 13 of the other fan is located on the opposite side of said flange. Such number of blades will be secured to each flange as may be desired to complete the set.

A driver is rigidly secured to the shaft and projects between members spaced apart and rigidly secured to the flange, this driver being located in proximity to said spaced members so that by a slight movement in one direction it will press loosely against one of said members to drive the fan and when the speed of the shaft is decreased the fan traveling ahead will cause the other spaced member to rest loosely against the driver and the speed of the fan is thus retarded. This driver may be constructed in various ways, in a satisfactory form of construction and as shown herein there being a driver hub 16 that is rigidly secured to the shaft and that has arms 17—18 projecting preferably from diametrically opposite sides thereof. Each of these arms is constructed so that it may be employed as a driving arm but in most instances one arm only will be employed as a driving arm while the other will constitute a counterbalance arm. In the form of construction shown herein the outer ends of the arms 17 are offset from the opposite end of the arm and is secured to the hub while the arms 18 are straight. It is desired that the driving arm shall press against a fan blade at a point somewhat near the flange 14, and when the hub, as 12, is located on the same side of the flange as are the fan blades

- the offset arm 17 will be employed as the driving arm, but when the hub of the fan, as 13, is located on the opposite side of said flange then the arm 18 will be employed as 5 the driving arm. In this way it will be noted that the driving contact with the fan blades is in substantially the same place irrespective of that side of the flange which the hub is located on.
- 10 Each of the arms is formed with a driving head 19 at its outer end, each head being recessed upon opposite sides to receive a cushion 20, these cushions being located in the arms that are employed as driving 15 arms and the cushions resting loosely against a fan blade, as shown in the drawings. One of these cushions will act as a driving cushion to propel the fan forward and the other will act as a retarding cushion to prevent the fan from over-running, that is, from rotating faster than the shaft 20 when the speed of the latter is decreased. The arm 17 or 18 on the opposite side of the hub from the arm that is employed as the 25 driving arm will constitute a counterbalance arm to serve in balancing and steady-ing the movement of the driving arm in its rotation.

While I have shown and described here-30 in a satisfactory means for loosely connecting the driving shaft with the fan, it is apparent to me that this loose driving connection may be obtained in various ways and I do not, therefore, limit my invention 35 to the exact means of effecting this connection herein shown and described.

I claim—

1. A fan rotatably mounted, a member mounted to move independently of said fan 40 and pressing loosely against it to rotate it, and means for driving said member.
2. A fan rotatably mounted and includ-ing a blade, a member to move independ-45 ently of said fan and pressing loosely against said blade to rotate the fan, and means for driving said member.
3. A fan rotatably mounted and includ-ing a number of blades, a member movable 50 independently of said fan and extending be-tween said blades and pressing loosely against a blade to rotate it, and means for driving said member.
4. A fan rotatably mounted and includ-ing a number of blades, a member movable 55 independently of said fan and extending between two of said blades, and adapted to engage both of said blades to drive the fan or retard its movement, and means for driv-ing said member.
- 60 5. A fan rotatably mounted, a shaft mounted to rotate independently of said fan, and means rigid with said shaft and loosely engaging said fan to rotate it.

6. A shaft with means for driving it, a fan loosely supported on the shaft, and 65 means rigid with the shaft and extending to press loosely against said fan to ro-tate it.

7. A shaft with means for driving it, a fan loosely supported on the shaft, and an 70 arm rigidly connected with the shaft and projecting therefrom and pressing loosely against said fan to rotate it.

8. A shaft with means for driving it, a fan loosely supported on the shaft and con-sisting of a plural number of blades, and an 75 arm rigidly connected with the shaft and projecting between two of said blades in proximity thereto to press loosely against them for driving and retarding operations. 80

9. A shaft with means for driving it, a fan loosely supported on the shaft and hav-ing spaced members thereon, and means rigid with the shaft and projecting between 85 said spaced members to loosely engage them for driving and retarding purposes.

10. A shaft with means for driving it, a fan loosely supported on the shaft, said fan having spaced members rigidly sup-90 ported thereby, means rigid with the shaft and projecting between said spaced mem-bers, and a cushioning member supported by said driving means to loosely engage said spaced members to rotate the fan.

11. A shaft with means for driving it, a fan loosely supported on the shaft and hav-ing members rigidly secured thereto and spaced apart thereon, arms rigidly secured to the shaft and projecting in opposite di-95 rections therefrom, one of said arms extend-ing between said spaced members to press loosely against them for driving purposes.

12. A shaft with means for driving it, fans supported on the shaft and having means secured thereto and spaced apart 100 thereon, arms rigidly secured to the shaft and projecting in opposite directions therefrom, the outer end of one arm being offset from its opposite end, and one of said arms extending between said spaced member to 105 press against them for driving purposes.

13. A shaft with means for driving it, a hub loosely supported on the shaft, a flange project-ing from one end of said hub, fan 110 blades secured to said flange, and a driving member rigidly secured to the shaft and having arms projecting in opposite direc-tions therefrom with the outer ends of the 115 arms arranged to press against the fan blades in the same place with the driving member in different positions with respect to said hub on said shaft.

IRA H. SPENCER.
